UNITED STATES PATENT OFFICE.

HARRY THAYER KINGSBURY, OF KEENE, NEW HAMPSHIRE.

DESIGN FOR A BODY-BLANK FOR TOY HOOK-AND-LADDER TRUCKS.

SPECIFICATION forming part of Design No. 32,932, dated July 10, 1900.

Application filed June 14, 1900. Serial No. 20,366. Term of patent 14 years.

To all whom it may concern:

Be it known that I, HARRY THAYER KINGSBURY, a citizen of the United States, residing at Keene, in the county of Cheshire, State of New Hampshire, have invented and produced a certain new and original Design for Body-Blanks for Toy Hook-and-Ladder Trucks, of which the following is a description, reference being had to the accompanying drawing 10 and to the letters of reference marked thereon.

My invention relates to a new and original design for body-blanks for toy hook-and-ladder trucks; and it consists of a blank of the shape and configuration hereinafter 15 described, and illustrated in the accompanying drawing, in which the figure illustrates a plan view of a body-blank for toy hook-and-ladder trucks embodying my design.

In the drawing, A represents the blank as 20 a whole, having at either end the projecting side portions B, which form the sides of the truck when bent up and over to proper position. Each side, between the points B and B,

is formed with the openings C and adjacent the opening C nearest each end with the inclined transverse slit a. The central portion of the body-blank A is cut out, as shown, to form the projecting tongue D, each having the projecting lugs b. Said central portion has also the openings c, as shown. 25 30

The leading feature of the design consists of the central portion with the projecting tongues D.

Having thus described my invention, what I claim, and desire to secure by Letters Patent, is— 35

The design for a body-blank for toy hook-and-ladder trucks; substantially as shown and described.

In testimony whereof I affix my signature 40 in presence of two witnesses.

HARRY THAYER KINGSBURY.

Witnesses:

W. L. MASON,
FRANK WILDER.
